MOTOR COOLING SYSTEM

Dorhl H. Coy, Jackson, Ohio

Application October 4, 1937, Serial No. 167,179

6 Claims. (Cl. 123—174)

This invention relates broadly to motor cooling systems and is more particularly directed to motor cooling systems employing a liquid cooling medium, a heat dissipating radiator and a rotatable fan for causing the forced circulation of air through the latter. This type of cooling system is generally employed in motor vehicles and tractors and it is an object of the invention to improve the operation of the system, particularly when the vehicles are used in cool or cold weather.

It is an object of the invention to provide a fan for a motor cooling system, which is formed with adjustable blades and thermally responsive mechanism for automatically varying the pitch mechanism of the blades. The pitch varying mechanism is controlled by the temperature of the water in the lower portion of the radiator where the temperature is lowest. This is highly desirable since it is a well known fact that the cooling medium at this point may be near a freezing temperature, while in the water jacket, the temperature may be high.

An object of the invention also rests in the provision of means for assisting the circulation of the cooling medium which is operatively connected with the pitch varying mechanism whereby the speed and direction of circulation of the cooling medium is changed in accordance with changes in temperature of the radiator.

A further object of the invention resides in the employment of a collector and conduit for transferring air from the lower portion of the radiator where the temperature is lowest, to the vicinity of the thermally responsive mechanism.

Other objects will be apparent from the following description when considered in connection with the accompanying drawings, in which:

Fig. 1 is a view in side elevation of the fan and cooperating mechanism formed in accordance with the present invention, the same being installed on a motor vehicle;

Fig. 2 is a horizontal sectional view on the plane indicated by the line II—II of Fig. 1;

Fig. 3 is a vertical transverse sectional view on the plane indicated by the line III—III of Fig. 2;

Fig. 4 is a vertical longitudinal sectional view on the plane indicated by the line IV—IV of Fig. 2;

Fig. 5 is a detail sectional view on the plane indicated by the line V—V of Fig. 3;

Fig. 6 is a vertical transverse sectional view through the means for assisting the circulation of the cooling medium, the plane of the section being indicated by the line VI—VI of Fig. 2;

Fig. 7 is a perspective view of a combined air collector and conduit used to transfer air from the lower portion of the radiator to the thermally responsive mechanism;

Fig. 8 is a diagrammatic view illustrating the direction of air and water flow when the lower portion of the radiator is at an extremely low temperature.

Referring more particularly to the drawings, the numeral 1 designates the radiator of a motor cooling system and the numeral 2, the motor to which the cooling system has been applied. Upper and lower flexible hose sections 3 and 4 connect the water jacket of the motor with the radiator and provide for the circulation of a liquid cooling medium from one to the other. This mechanism is of the type generally employed in motor vehicles and a more detailed description thereof is believed to be unnecessary.

Secured to the front wall of the motor 2 is a metallic casting 5 which constitutes the water pump housing. This housing is formed with a tubular projection 6 to which is connected one end of the lower hose leading from the radiator. Provided also in connection with the housing 5 is a forwardly disposed bracket 7 forming a bearing to rotatably support the water pump and fan shaft 8. The body of the housing 5 in registration with the bearing 7 is provided with an apertured boss 9 to receive the inner portion of the shaft 8 and function as a second bearing therefor, the boss 9 including a packed gland 10 to prevent the escape of cooling medium around the shaft.

The outer end of the shaft 8 has joined thereto by means of screw threads 11, a hollow, substantially cylindrical body 12 which forms the hub of the air circulating fan designated in its entirety by the numeral 13. Adjacent the rear end of the hub, the same is provided with an annular groove to receive an endless driving belt 14 used to impart rotation to the fan from the crank shaft (not shown) of the motor. The continuous outer wall of the hub is formed to include a plurality of radiating bosses 15, each having a central bore 16 in registration with the axial center of the hub. The bores 16 each rotatably receives a stub shaft 17 which has a fan blade 18 riveted or otherwise secured to the outer end thereof. A packing is provided at the outer end of each boss 15 to prevent the loss of oil or other lubricating medium positioned within the hub. The outer edge of the hub terminates in an inwardly extending flange 19 which also serves to retain the lubricating medium within the hub.

The inner end of each blade shaft 17 is squared

as at 20 to non-rotatably receive a gear segment 21, the inner extremity of the shafts being threaded and provided with nuts 22 to hold the segments 21 in place on the shafts. These latter 5 two elements also serve to resist the outward movement of the blades in response to the centrifugal force.

The teeth of the segments 21 are disposed in meshing engagement with a bevel gear 23. This 10 gear is secured by a nut 24 to the outer portion of a rod 25 rotatably positioned in a bore extending axially of the shaft 8. It will be apparent at this point that rotary movement on the part of the gear 23 will result in similar movement being 15 transmitted to the blades 18 by means of the segments 21. This movement of the blades will change the pitch thereof and alter the volume of air circulated by the fan. In some instances, the pitch may be reduced to such a degree that no 20 air is circulated and at times of severe drops in temperature, the pitch may be reversed to cause warmer air from around the engine to pass through the radiator.

It has been found desirable to control the 25 pitch of the fan blades by the temperature of the air passing through a portion of the radiator and to this end, the hub is provided with a forwardly extending cap 26. A thermostat 27, of the collapsible bellows type in this instance, has 30 one end rigidly secured to the inner side of the forward wall of the cap 26. The free end of the thermostat includes a tubular member 28 which is loosely positioned on the reduced end of the rod 25 to limit the movement of the thermostat 35 to but a single plane. Pivotal secured at one end to the free end of the thermostat is a pair of links 29, the opposite ends thereof being connected as at 30 to one branch of a pair of bell crank levers 31. The levers are pivotally supported on 40 opposite sides of the hub in brackets 32 secured thereto by screws 33. The second branches of the levers 31 are joined by means of the universal connections 34 with the gear 23. By this mechanism, back and forth movement on the part of 45 the free end of the thermostat is transformed into rotary movement on the part of the gear 23 and will be transmitted to the blades by the segments as before mentioned.

The portion of the radiator selected as the most 50 desirable to control the fan is the lower portion. This selection was made since it is readily recognized that the water is at its lowest temperature when in this location. Frequently in cold weather, the water in this region is at a very low temperature, sometimes frozen, while that in the water jacket may be at the boiling point. The 55 temperature of this air will be similar to that of the water at this point whether the latter is hot or cold. When these conditions prevail, many of the antifreeze compounds will boil out and be wasted. Therefore a combined air collector and 60 conduit member 35 is provided to conduct air which passes through the lower portion of the radiator to the location of the thermostat. The 65 member 35 includes a transversely extending branch 36 to the center of which is connected a vertical branch 37. The former is closed on its bottom, top and back walls and the open front wall is held adjacent the back of the radiator. 70 The vertical branch is tubular in form and communicates at its lower end with the interior of the horizontal branch. The top end of the branch 37 terminates in a rearwardly facing opening 37a from out of which the fan will draw

air. The member 35 is secured to the radiator by means of long slender bolts 35a.

Substantially midway of its height, the branch 37 is provided with a cup-like enlargement 38 to receive the cap and thermostat carried by the fan hub. The front wall of the cap has an opening 39 formed therein to admit air to the interior thereof while the side wall has an opening 40 to permit the escape of the air entering the opening 39. The edges of the openings are flared in such a manner as to force a certain amount of air therethrough to provide a continuous circulation of air around the thermostat while the engine is running.

It has also been found desirable to modify the circulation of water when drastic changes in the weather and changes in temperature incident to operating the engine occur. To provide for these changes in water circulation, the inner end of the shaft 8 rigidly receives the body 41 of the 15 water pump impeller. This body is also hollow and is provided with a plurality of transversely extending branches 42 which rotatably support the shanks 43 of impeller vanes 44. Packing nuts 45 are provided around the vane shanks 43 to prevent the seepage of cooling fluid into the interior of the body 41. The inner end of each of the shanks 43 has a bevel pinion 46 secured thereto which is arranged in meshing engagement with a similar pinion 47 secured to the inner end of the rod 25. It will be seen that as the thermostat 20 imparts rotary movement to the gear 23, as before described, similar movement will be transmitted by the rod 25 to the pinion 47 and consequently to the vanes by the pinions 46. This 25 movement will vary the pitch of the vanes and thereby cause a faster or slower circulation of cooling medium through the radiator and water jacket.

The rear open end of the impeller body has 30 internal threads 48 formed therein to receive the thread portion of a cap 49. The chamber within the body 41 can be packed with a semisolid lubricant and the cap put in place before the water pump and fan is installed. This lubricant should 45 be sufficient to last for the ordinary life of the vehicle.

The changes in the pitch of the impeller vanes occur simultaneously with those of the fan blade and are in substantially the same proportion. The mechanism herein set forth provides means for improving the operation of the engine by decreasing the time period required for warming up the engine as well as reducing the volume of air circulated when the temperature of the atmosphere is low. As diagrammatically illustrated in Fig. 8, if the temperature should fall to a very low extreme, the pitch of the blades and water pump vanes is reversed to cause a reversal of the direction of circulation of the air and water. The 50 latter is highly desirable when the cooling medium has commenced to freeze in the lower portion of the radiator.

While there has been shown and described, in its preferred form, apparatus for carrying out the present invention, it will be understood that numerous minor changes may be made in the mechanism without departing from the spirit and scope of the invention as set forth in the following claims.

What is claimed is:

1. In a motor cooling system having a radiator, a fan shaft, a fan hub mounted on said shaft for rotation adjacent said radiator, a plurality of fan blades adjustably carried by said hub, ther- 75

mo-responsive mechanism carried by said hub, a water impeller body carried by said fan shaft for rotation therewith, vanes adjustably supported in connection with said impeller body, and motion transmitting means connecting said fan blades and said vanes with said thermo-responsive mechanism.

5. A combined air circulating fan and water impeller for engine cooling systems comprising a rotatably mounted tubular shaft, a fan hub secured to one end of said shaft, an impeller body

10 secured to the opposite end of said shaft, a plurality of fan blades pivotally mounted in connection with said hub, a thermostat supported by

15 said hub, a second shaft extending through said tubular shaft, gear means carried at opposite ends of said second shaft, means for rotating said second shaft in response to movement on the part

20 of said thermostat, vanes pivotally mounted on said impeller body, and pinions connecting said fan blades and said vanes with the corresponding

25 gears on said second shaft.

2. A combined air circulating fan and water impeller for engine cooling systems comprising a

30 rotatably mounted tubular shaft, a fan hub secured to one end of said shaft, an impeller body

35 secured to the opposite end of said shaft, a plurality of fan blades pivotally mounted in connection with said hub, a thermostat supported by

40 said hub, a second shaft extending through said tubular shaft, gear means carried at opposite ends of said second shaft, means for rotating said second shaft in response to movement on the part

45 of said thermostat, vanes pivotally mounted on said impeller body, and pinions connecting said fan blades and said vanes with the corresponding

50 gears on said second shaft.

3. The combination with an engine cooling

55 system having a radiator, a fan having variable

pitch blades and thermostatic means for varying

60 the pitch of said blades, of means for collecting

65 and conducting air which has passed through the lower portion of said radiator to the region of

70 said thermostatic means.

4. A combined air circulating fan and water impeller for engine cooling systems comprising a

75 rotatably mounted tubular shaft, a fan hub secured to one end of said shaft, an impeller body

80 secured to the opposite end of said shaft, a plurality of fan blades pivotally mounted in connection with said hub, a thermostat supported by

85 said hub, a second shaft extending through said

tubular shaft, gear means carried at opposite ends of said second shaft, means for rotating said second shaft in response to movement on the part of said thermostat, vanes pivotally mounted on said impeller body, pinions connecting said fan 5 blades and said vanes with the corresponding gears on said second shaft, and means for conducting air from the lower portion of the radiator for said engine to the vicinity of said thermostat.

10

5. In a motor cooling system having a radiator

in liquid communication with the motor, a rotatable fan having angularly adjustable blades positioned adjacent said radiator, thermo-responsive

15 means for controlling the angularity of the fan blades, and an air conduit positioned at the rear

of said radiator, the inlet to said conduit being

disposed in a position to receive air passing

10 through the lower portion of said radiator, said

thermo-responsive means being disposed in said

20 conduit to be intimately engaged by air passing

therethrough.

6. In a motor cooling system having a radiator

in liquid communication with the motor, a rotatable fan having angularly adjustable blades posi-

25 tioned adjacent said radiator, thermo-responsive

means for controlling the angularity of the fan

blades, an air conduit positioned with the inlet

thereof in registration with a restricted portion

20 of the radiator at the lower end thereof, the out-

let of said conduit being in registration with the

outer portion of said fan blades, said thermo-

25 responsive means being disposed in said conduit

between the inlet and outlet to be intimately con-

30 tacted by air passing through said conduit.
